US00D525472S

(12) United States Design Patent (10) Patent No.: US D525,472 S
Beesley et al. (45) Date of Patent: * Jul. 25, 2006

(54) COMBINATION BREAD TOASTER AND STEAMER DEVICE

5,673,608 A 10/1997 DeMars
 5,694,831 A 12/1997 Haroun et al.

(75) Inventors: Brian K. Beesley, Salt Lake City, UT (US); Claude Brandt, Salt Lake City, UT (US); Liao Zhiwen, Foshan (CN)

(73) Assignee: Back to Basics Products, Inc., Bluffdale, UT (US)

() Term: 14 Years

(21) Appl. No.: 29/234,431

(22) Filed: Jul. 14, 2005

Related U.S. Application Data

(63) Continuation of application No. 11/155,007, filed on Jun. 15, 2005, and a continuation of application No. 11/154,282, filed on Jun. 15, 2005.

(57) CLAIM

The ornamental design for a combination bread toaster and steamer device, as shown and described.

DESCRIPTION

FIG. 1 is a perspective view of the combination bread toaster and steamer device in accordance with our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

1 Claim, 6 Drawing Sheets
